UNITED STATES PATENT OFFICE

CLIFFORD L. MEYER, OF BELLEVUE, PENNSYLVANIA

SUSPENDERS

Application filed September 5, 1930. Serial No. 479,914.

The object which I have in view is the provision of a new and improved suspender for holding in place trousers and the like, and which will be of a more pleasing appearance, greater durability and also will be more comfortable to the wearer.

Among the characteristic features of my improved suspender are the following.

The shoulder straps are formed of braided material, the strands being preferably formed of tubular textile material, such as tubular cotton braid with a covering of rayon or silk.

The shoulder straps are preferably each formed of four strands of this material, two lengths of material being used, such lengths being doubled with their centers looped over the bar of the front buckle. At the rear the two straps are united by braiding the eight strands together and the united material is sewed between the two leather pads.

The upper end of the back strap, which is preferably elastic webbing, is sewed to these pads and its lower end is looped through the wire loop which forms the upper end of the back fork, and the end of the back strap is connected to a slideable buckle mounted on the back strap. The front forks may be provided with straps of leather or other material which are engaged with the front buckles, or with other suitable means for adjustment as to length.

Other features of novelty will appear from the following description.

In the accompanying drawings wherein I have illustrated the practical embodiments of the principles of my invention, Fig. 1 is a broken view of the suspender.

Fig. 2 is a detail on enlarged scale showing the method of attaching the shoulder straps to the front buckles.

Fig. 3 is a detail showing the attachment of the united shoulder straps at the rear to the back strap of the suspender, one of the pads being removed to better show the structure.

Referring to the drawings the shoulder straps are each formed by braiding together four strands of suitable material, these 50 strands being indicated in the case of the

right hand shoulder strap in Fig. 1 as 1, 2, 3 and 4 and on the left hand shoulder strap as 1a, 2a, 3a and 4a. These strands are formed by looping two lengths of the material over the cross bar 5 of the front buckle 6 as best shown in Fig. 2. The material for these strands is preferably tubular fabric or other braid, such for instance as tubular cotton braid which may be provided with a woven covering of rayon, silk or the like. The strands may be of different color so as to give the shoulder straps a more ornamental appearance.

If desired strands of leather of other material may be used.

The united ends of the two shoulder straps are sewed between the leather or other pads 7 and 8 and the upper end of the back strap 9 is also sewed between these two pads. The back strap 9 is slipped through the wire loop 10 of the rear fork 11 and the lower end of the back strap is attached to the slideable buckle 12 which works on the back strap, thus making the suspender adjustable at the rear as to length.

The front forks 13 are provided with wire loops 14 to which are attached the front straps 15 which are buckled into the buckles 6, being adjustable therein so as to give a double adjustment for length, front and rear, for the suspender.

The advantages of my improved structure are numerous.

Thus the braiding of the strands together provides an elastic structure which has an elasticity in the case of cotton and rayon strands amounting to approximately ten per cent of its length.

The shoulders of the wearer slip and move easily in the shoulder straps, thus preventing any binding or undue rubbing which in an ordinary suspender causes a great deal of discomfort.

Again the braided structure is soft and comfortable to the body of the wearer and does not present the sharp straight edges which a suspender formed with flat webbing has and which tend to go into the shoulders and body of the wearer.

Furthermore the braiding of the strands

of the two shoulder straps together at the rear and attaching the pads thereto forms a union which will not be ripped or torn apart but which is permanent and very substantial.

5 The double adjustment, in front and rear, enables the suspender to be accurately adjusted to the correct length to properly support the trousers and to insure comfort for the wearer.

10 What I claim is:—

1. In a suspender for supporting garments from the shoulders of the wearer, the combination with the front forks and the rear fork and a bar connected to each of the

15 front forks, of shoulder straps formed of a plurality of lengths of material doubled through said bar and braided together, the rear ends of the shoulder straps being connected to the rear fork.

20 2. In a suspender for supporting garments from the shoulders of the wearer, the combination with the front forks and the rear fork and a bar connected to each of the

25 front forks, of shoulder straps formed of a plurality of lengths of material doubled through said bar and braided together, the rear ends of the shoulder straps being connected together by braiding the strands of

30 the two straps into a united structure, and an elastic connection between the said united structure and the rear fork.

35 3. In a suspender for supporting garments from the shoulders of the wearer, the combination with the front forks and the rear fork, of straps attached to the front forks and buckles adjustable on said straps, shoulder straps formed of a plurality of lengths of material doubled over the bars of the buckles and braided together, and a connection between the rear ends of the shoulder straps and the rear fork.

Signed at Pittsburgh, Pa., this 4th day of September, 1930.

45 CLIFFORD L. MEYER.
